FOLDING BASKET CARRIER

Sylvan N. Goldman, Oklahoma City, Okla.

Application November 6, 1946, Serial No. 708,148

8 Claims. (Cl. 280—42)

1

This invention relates to carts especially employed in grocery stores. It has been proposed to build carts or carriers for use by customers in grocery stores for conveying purchases, but since such carts must be of a predetermined length and width to support the wire baskets carried thereon a large area is required to store the carts. Due to the limited floor surface of a great many stores it is necessary to either limit the number of carriers or the business equipment.

It is an object of the present invention to construct carriers which may be readily collapsed or reformed by the manipulation of certain elements so that a number of carts may be stored in the space formerly occupied by a single carrier.

Another object of the invention is the provision of a carrier for use by customers in a grocery or other store in which the raising of a wire basket-supporting grid to a vertical position for reception by sockets at one side of the carrier will permit folding of the carrier so that the sides thereof and the wheels may be moved into close association when the carriers are stored, thereby reducing the storage space formerly required.

A further object of the invention is the provision of a collapsible or foldable sturdy carrier in which a wire basket-supporting grid is employed for retaining the side walls, in the form of metal frame-works, in an extended position when the carrier is used as a conveyance but which grid may be tilted to a vertical position and lowered in sockets in one side wall of the carrier to permit folding of said carrier, the handle bar for operating the carrier being tiltably mounted so that the bar may be moved to an inoperative and vertical position when the carrier is folded.

The invention consists in the novel construction, arrangement and combinations of parts hereinafter more particularly described and claimed.

In the drawings:

Figure 1 is a side view in elevation of a carrier constructed in accordance with the principles of my invention.

Figure 2 is a front end view in elevation of the carrier.

Figure 3 is a plan view of the carrier.

Figure 4 is a transverse vertical section taken along the line 4—4 of Figure 1.

Figure 5 is a transverse vertical section taken along the line 5—5 of Figure 1.

Figure 6 is a side view in elevation of the carrier shown in folded condition, and

2

Figure 7 is a rear end view in elevation of the folded carrier shown in Figure 6.

Referring more particularly to the drawings, 10 and 11 designate a pair of side walls, each wall being in the form of a frame-work made of metal. Each wall is mounted on a base 12 supported by pairs of wheels 13 and 14. The side walls are connected together by front and rear lazy tongs, the tongs being designated respectively by the numerals 15 and 16.

Each side wall includes the base 12 in the form of a flat bar to which at the lower ends are welded spaced parallel vertical bars 20 and 21. Each vertical bar has an offset upper end 22 which is provided with a horizontal flange 23 welded to the bridge portion of an inverted horizontal channel iron. The channel iron of the side wall 10 is designated by the numeral 24 while a similar channel iron 25 is included in the side wall 11. A curved brace bar 26 has the lower end secured to the offset 22 of the vertical bar 20 of each side wall. The other end of the brace bar has a horizontal flange 27 welded to the inner end of channel bar 24 or 25. The free end 28 of the brace bar is turned upwardly as shown. A brace 29 at the front end of each side wall has the lower end secured to the offset 22 of the vertical bar 21. The upper end of said brace bar has a horizontal flange 30 and a vertical flange 31. The flange 30 of one brace bar is welded to the front end of the channel member 24 while the flange 30 of the other brace bar is welded to the channel bar 25. Both side walls 10 and 11 are substantially identical in construction.

A guide 32 having a vertical groove 33 is secured to each of the offsets 22 of the vertical bars 20 and 21. The lazy tongs 15 at the front of the carrier include diagonally arranged links 35 and 36 which have oppositely disposed offset portions 37 pivoted on a pin or bolt 38. The link 35 has its lower end pivoted on a bolt carried by the lower portion of one of the bars or legs 21. The other link 36 is pivoted on a bolt 40 carried by the other bar 21 at the front of the carrier. Each of the links 35 and 36 has a pin 41 at the upper end thereof riding in one of the grooves 33 in the guides 32. The lower end of each groove 33 is closed to form a stop for limiting the downward movement of the pin when the carrier is in an operative position, as shown in Figure 4. On the other hand, the pins ride to the upper ends of the grooves when the carrier is folded (Fig. 6).

The lazy tongs 16 at the rear of the carrier is

identical in construction with the lazy tongs 15 at the front and therefore the same reference numerals are applied to similar elements of both lazy tongs.

The lower ends of the links 35 of both tongs are connected together by brace bars 42 and gusset plates 43 at the ends of said bars 42. The upper ends of the links 35 are connected together by bars 44 and gusset plates 45. The lower ends of the links 36 and the upper ends of the links 10 are connected together in the same manner as are the links 35.

Gusset plates 49 are welded to the lower ends of the vertical bars 20 and 21 of each of the side walls of the carrier. The plates are also secured to the base bars 12 thereby fixing the vertical bars rigidly in position.

Bumpers 50 which may be in the form of rubber or wooden rollers 51 are carried by axles 52. A bracket 53 connected to each front vertical bar 21 has a bearing for the upper end of the axle 52. A member 54 braces the bracket 53. The lower end of each vertical bar 21 has a horizontal flange 55 extending forwardly of the carrier and said flanges have bearings for the lower ends of the axles 52. The bumpers, thus supported, project forwardly of the carrier.

A grid generally designated by the numeral 60 is composed of longitudinal parallel bars 61 and 62 and transverse bars as shown in Figure 3. The transverse bars 63 having one end inturned to provide depending lips 64—a.

The channel bar 25 has spaced slots or sockets 65 (Fig. 4) for receiving the lips 64—a. The channel bar 24 has a plurality of spaced openings or slots 66 to receive the free ends 67 of all of the bars 63 and 64 at that side of the grid where the channel bar 24 is located. The free ends 67 of the bars 63 and 64 are adjacent the outer flange of the channel bar 24 and cooperate with the lips 64—a for retaining the side walls of the carrier in spaced relation and said carrier in operative running condition.

A handle bar 70 of cylindrical form has a longitudinal slot 70—a and a pair of depending spaced flanges 71 pivoted on a pin 72 carried by a bar 73 which has a curved free end 74 located within the hollow bar 70. The bar 73 is secured at right angles to a vertical bracket 75 having a horizontal arm 76 secured to the inner flange of the channel bar 24.

A bar 77 has a notch 78 which receives a pin 79 carried by a pair of flanges 80 depending from and formed integrally with the hollow handle bar 70. The upper end of the bar 77 is semicircular as shown at 81, and is disposed in the handle bar 70. A pin 82 is mounted in the upper end of the bar and disposed within the handle bar with the ends of the pin in engagement with the inner wall of the hollow handle bar at diametrically opposite points.

A bracket 83 is secured to the bar 77 at right angles thereto. A horizontal arm 84 of the bracket is secured to the inner flange of the channel member 25 (Figure 2).

Guards 85 to hold the wire baskets 86 on the rack or grid 60 are hingedly mounted on pins 87 carried by the upturned flanges 28 and 31 at the upper ends of the respective braces 26 and 29 (Figure 1) associated with the pairs of vertical bars 20 and 21. Each guard consists of a flat strap of metal which has the free end bent inwardly as shown at 88, in Figure 1, and the bent ends are hingedly mounted on the pins 87.

Each front wheel 14 is mounted on an axle 90

carried by a bracket 91 which is swivelled on the flange 55 (Figs. 1 and 2). Each rear wheel 13 is mounted on an axle 92 carried by a guard plate 93 and a brace bar 94, (Figs. 6 and 7).

5 The operation of my device is as follows:

The carrier is illustrated in Figures 1 to 4 inclusive as ready for use by a customer in any type of store or business place with the handle bar 70 and grid in operative positions for retaining the side walls or frames in spaced parallel relation so that the baskets 86 may be supported on the grid. The guards 85 are placed in a horizontal plane above the grid to maintain the baskets on the carrier.

15 When not in use, the carriers are folded and placed in storage. In order to fold the carrier, the baskets 86 are removed and stacked within each other. The portion of the grid adjacent the channel iron 25 is raised as shown in dotted lines in Figure 2, with the walls of the slots or sockets 66 in the channel iron 24 acting as sliding pivots for the free ends 67 of the transverse bars 63 and 64 of the grid 60. When the grid has been elevated to a vertical position, the free portions 67 of the transverse bars will have been lowered to the utmost and the longitudinal bar 62 of the grid will rest upon the top of the inverted channel iron 24.

20 The release of the grid will permit the side frames or walls to be moved toward each other in parallel relation due to the action of the lazy 30 tongs 15 and 16. As the side frames are forced toward each other the pins 41 will ride upwardly in the slots 33 of the guides 32 carried by the respective uprights or vertical bars 20 and 21. During this operation, the hollow handle bar will slide on the curved upper edge 81 of the bar 77 (Fig. 5), while the pin 79 is moving out of the slot 78 in the depending flanges 80 rigid with the hollow bar 70. At the same time the flanges 71 on the other 35 end of the bar 70 are pivoting on the pin 72. As the handle 70 moves toward the right in Figure 5, the pin 82 guides the handle bar downwardly to the position shown in Figures 6 and 7, while the bar 77 rides through the slot 70—a, whence the 40 carrier will be collapsed completely and ready for storage.

45 When restoring the carrier to its normal operative condition, the steps just enumerated are reversed. In other words, the side frames are pulled apart and guided in parallel relation by the lazy tongs 15 and 16. The pins 41 riding downwardly in the slot 33 of the guides 32 will reach the lower closed ends of said slots and will limit the outward movement of the side frames. The handle bar 50 slides automatically into position.

55 The grid 60 is lifted and moved to a horizontal position and the lips 64—a on one end of each of the transverse bars 63 are seated in the sockets 65 formed in the channel bar 25. Thus the pins 60 41 carried by the upper ends of the links forming the lazy tongs cooperate with the grid and the channel irons 24 and 25 for maintaining the carrier in working condition.

65 The pin 79 is in engagement with the walls of the notches 78 and the handle bar 70 is restrained from sliding movement when the carrier has been assembled.

When the carrier has been folded the guards 85 are moved from the horizontal positions shown in Figures 1 to 4 inclusive, to the vertical positions shown in Figures 6 and 7.

70 Although a preferred and practical embodiment of the invention is disclosed herein, it is to be understood that various modifications may be made within the scope of the appended claims.

I claim:

1. A foldable wheeled carrier comprising a pair of spaced side frames, lazy tongs connecting the side frames together so that said frames may be moved toward or away from each other in parallel relation, a basket supporting grid removably mounted on the tops of the frames, cooperating means on the grid and frames for aiding in retaining the frames in spaced relation, a hollow handle bar, a bracket secured to each frame and extending upwardly therefrom, means pivotally connecting one end of the hollow bar on one end of one bracket and means slidably connecting the other end of the hollow bar with the other bracket.

2. A foldable wheeled carrier comprising a pair of spaced side frames, lazy tongs connecting the side frames together so that said frames may be moved toward or away from each other in parallel relation, a basket supporting grid formed of longitudinal bars and transverse bars connected to the longitudinal bars with the free ends of the transverse bars projecting beyond the longitudinal bars, the upper edge of each side frame having sockets therein to receive the adjacent ends of the transverse bars.

3. A foldable wheeled carrier comprising a pair of spaced side frames, lazy tongs connecting the side frames together so that said frames may be moved toward or away from each other in parallel relation, a basket supporting grid formed of longitudinal bars and transverse bars connected to the longitudinal bars with the free ends of the transverse bars projecting beyond the longitudinal bars, a lip depending from one end of certain transverse bars, the upper edge of one side frame having sockets to receive the lips, the upper edge of the other side frame having sockets to receive the other ends of the transverse bars, a handle bar and cooperating means on the bar and frames for slidably and tiltably mounting the bar on the frame.

4. A foldable wheeled carrier comprising a pair of spaced side frames, lazy tongs connecting the side frames together so that said frames may be moved toward or away from each other in parallel relation, a basket supporting grid formed of longitudinal bars and transverse bars connected to the longitudinal bars with the free ends of the transverse bars projecting beyond the longitudinal bars, a lip depending from one end of certain transverse bars, the upper edge of one side frame having sockets to receive the lips, the upper edge of the other side frame having sockets to receive the other ends of the transverse bars, said grid being tiltable to a vertical position when the carrier is folded so that the last-mentioned ends of the transverse bars will move through the associated sockets until a longitudinal bar rests on the top of a side frame.

5. A foldable wheeled carrier comprising a pair of spaced side frames, pairs of lazy tongs connecting the side frames together, each frame having an inverted channel bar at the top thereof, said channel bars provided with spaced slots, a basket-supporting grid including transverse bars, a lip on an end of certain transverse bars received by the slots in one channel bar, the other ends of the transverse bars being received by the slots

in the other channel bar, said grid being tiltable before the carrier is folded so that the last-mentioned ends of the transverse bars will slide through the associated slots and retain the grid in a vertical position, a handle bar, and cooperating means on the bar and channel bars for slidably and tiltably mounting the handle bar on the channel bars.

10 6. A foldable wheeled carrier comprising a pair of spaced side frames, pairs of lazy tongs connecting the side frames together, each frame having an inverted channel bar at the top thereof, said channel bars provided with spaced slots, a basket supporting grid including transverse bars, a lip on an end of certain transverse bars received by the slots in one channel bar, the other ends of the transverse bars being received by the slots in the other channel bar, said grid being tiltable before the carrier is folded so that the last-mentioned ends of the transverse bars will slide through the associated slots and retain the grid in a vertical position, a bracket secured to an end of each channel bar, a handle bar having one end hingedly mounted on one bracket, and means on the other bracket for slidably connecting the other end of the handle bar on said bracket.

15 7. A foldable wheeled carrier comprising a pair of spaced side frames, lazy tongs connecting the side frames together so that said frames may be moved toward or away from each other in parallel relation, a basket supporting grid removably mounted on the tops of the frames, cooperating means on the grid and frames for aiding in retaining the frames in spaced relation, guards for supporting baskets on the grid when located in a horizontal plane, said guards being movable into vertical planes when the carrier is folded, a handle bar and cooperating means on the bar and frames for slidably and tiltably mounting the bar on the frame.

20 8. A foldable wheeled carrier comprising a pair of spaced side frames, pairs of lazy tongs connecting the side frames together, each frame having an inverted channel bar at the top thereof, a basket-supporting grid carried by the channel bars and aiding in retaining the frames in an operative position, one side edge of the grid being hingedly and slidably mounted on one channel bar so that the grid may be moved from a horizontal to a vertical position, cooperating means on the other channel bar for retaining the grid in a horizontal position, and a tilttable handle bar connected to the channel bars.
